UNITED STATES PATENT OFFICE.

HARRY J. DAHL, OF PHILADELPHIA, PENNSYLVANIA, ASSIGNOR TO UNION SPECIAL MACHINE COMPANY, OF CHICAGO, ILLINOIS, A CORPORATION OF ILLINOIS.

OVERSEAMING-MACHINE.

1,227,756.

Specification of Letters Patent. Patented May 29, 1917.

Application filed October 6, 1910. Serial No. 585,611.

To all whom it may concern:

Be it known that I, HARRY J. DAHL, a citizen of the United States, residing at Philadelphia, in the county of Philadelphia, 5 State of Pennsylvania, have invented certain new and useful Improvements in Overseaming-Machines, of which the following is a description, reference being had to the accompanying drawing and to the 10 letters and figures of reference marked thereon.

The invention relates to new and useful improvements in sewing machines, and more especially to overseaming machines 15 wherein stitches are formed around the edge of the material.

In forming an overedge seam, especially where the material is cut so as to leave a raw edge, it is found necessary to cause a 20 needle to enter the material at some distance from the raw edge of the material in order to provide proper anchorage for the threads.

I have found that by turning over the 25 edge of the material and causing the overseaming stitches to inclose or encircle said folded edge, I am able to produce an overseam which may be made very much narrower than the ordinary overseam and 30 which overseam will be greatly strengthened by the folded edge of the material.

An object of the present invention, is to provide an overseaming machine with means for folding the edge of the material and in- 35 closing said folded edge by overseaming stitches.

A further object of the invention, is to provide means for trimming the raw edge of a material, and means for folding said 40 trimmed edge on to the body of the material, and means for forming overseaming stitches around said folded edge.

I have also found it desirable in some instances to feed a tape on to the upper face 45 of the material, so that said tape will be partly inclosed by the overseaming stitches and the folded edges of the material, and a further object of the invention is to provide means for feeding a tape in advance of 50 the stitching mechanism, so that said tape may be partially inclosed in the overseam.

These and other objects will in part be obvious, and will in part be hereinafter more fully described.

55 In the drawings which show by way of

illustration, one embodiment of the invention;

Figure 1 is a side elevation of the front end of a machine embodying my improvements.

60

Fig. 2 is a top plan view of the work support, and a portion of the mechanism adjacent thereto.

Fig. 3 is a side view showing the trimmer blade, the edge of the work support and the 65 presser foot.

Fig. 4 is a perspective view of the throat plate, also showing the lower trimming blade.

Fig. 5 is a sectional view on the line x—x 70 of Fig. 4.

Fig. 6 is a sectional view through the throat plate in front of the folder on an enlarged scale, also showing the needle and loopers used in forming an overseam.

75

Fig. 7 is a top plan view of the presser foot.

Fig. 8 is a sectional view through an overseam formed on my machine.

Fig. 9 is a similar view shewing the application of the tape.

I have shown my invention as applied to an overseaming machine of the type illustrated in the Onderdonk Patent #962,974, granted June 28th, 1910. Said machine is 85 provided with a bed plate 1 on which the material rests during the stitching operation. The overhanging arm 2, supports the needle bar 3, which is vibrated in the usual way and carries a needle 4 at its lower end. 90 Coöperating with the needle above the work support is a thread carrying looper 5 and coöperating with the needle below the work support is a thread carrying looper 6. The loopers 5 and 6 coöperate with each other 95 so that the looper threads are joined at the edge of the material being overseamed.

The needle thread and also the looper threads are provided with ordinary tensions. By the adjusting of these tensions, the points 100 of the interlocking of the needle and looper threads may be varied. I prefer however, to adjust the tensions so that the thread of the looper 5 and the needle thread will be interlocked substantially at the needle punctures on the upper face of the material, and so that the thread of the looper 6 and the needle thread will be interlocked on the lower face of the material, substantially at 105 the needle puncture, and so also that the 110

looper threads will interlock at the folded edge of the material, as shown in Figs. 8 and 9. It is obvious however, that this interlocking of the threads or that the character of the overseaming stitch forming mechanism, may be varied without departing from the spirit of my invention.

The machine is also provided with a lower trimming blade 7, which is supported by a bracket 8 carried by the work support. Co-operating with the lower trimmer blade is an upper trimming blade 9 mounted on a lever 10, and operated in the manner fully described in the patent granted to Lansing Onderdonk December 24th, 1912, No. 1,048,204, which also shows the manner of adjusting the trimming blades for varying the width of the cut edge which is overstitched. The throat plate 10 which is mounted on the work support, is provided with the usual feed slots 11, through which operate the feed engaging surfaces 12, of the feed dog. The throat plate is also provided with a needle throat 13, and a stitched finger 14 around which the stitches are formed in the well known manner in this type of machine. At a point adjacent the needle throat 13, I have provided a folder 15, which as herein shown is formed integrally with the throat plate and projects upwardly and then laterally, gradually tapering from its receiving end to its delivery end adjacent the needle, so as to fold the edge of the material over on to the body of the material. The folder 15 is located so as to extend substantially from a point in front of the needle throat, to a point slightly in rear thereof, so that the looper thread after it is interlocked with the needle thread, will be laid over the folder 15 and said folder will therefore, take the place of the stitch finger usually carried on the presser foot. The folder extends however, as above noted, slightly in front of the needle throat, so that the material will be completely folded as it passes from the delivery end of the folder, and where the stitches are drawn down on to the folded edge.

From the above, it will be apparent that I have provided an overedge stitch forming mechanism which is adapted to join and cover edges of fabric sections. The folder holds both of the trimmed edges and presents the same to the stitching mechanism, so that said folded edges will be encircled by the overedge stitches. The trimmed edges of the folded over parts lie close to the line of needle puncture, but do not extend beyond the same, so that the entire fold in the fabric will be encircled or inclosed by said overedge stitching. In other words, the edges of the fabric sections are folded substantially to and within the limits of the width of the overedge stitches.

In order to assist in the folding of the

fabric, I have formed the upper edge of the lower trimming blade with a surface which inclines downwardly from the cutting point of the blade toward the front of the machine, and also toward the line of feed, and this cutting point is slightly raised above the plane of the work support.

By this positioning and construction of the lower trimming blade, the edge being trimmed will be slightly bent upwardly, and a preliminary fold started so that as the material passes into the folder, it may be folded completely on to the body of the material in a very short distance of travel. I am able thereby, to locate the trimming mechanism in the usual position relative to the stitching point, and locate the folder in the rear of the trimming blade so that the folding action occurs upon the cut edge of the material. I have shown herein the work support provided with the usual edge guide 16 for guiding the material to the trimming mechanism.

The presser foot 17 is supported by the usual presser bar 18. Said presser foot is cut away on the side thereof adjacent the stitching mechanism from a point in rear of the stitching mechanism, to a point in front of the trimming mechanism. An adjustable plate 19 is secured by means of a slot and screw connection 20 to the presser foot, and has a downwardly projecting portion which is substantially flush with the lower face of the foot, which downwardly projecting portion engages the material at a point adjacent the trimming mechanism. This plate may be adjusted toward and from the trimming blade. It will be noted that the presser foot is not in any way provided with a stitch forming tongue inasmuch as the folder secures this function as above noted.

It is sometimes desirable to stitch into the overseam a strengthening tape. In order that this tape may be folded with the edges of the material, I have provided a tape guide 21 in the forward part of the presser foot which is so disposed as to guide a tape with one edge thereof passing close to the trimming blades, and through the folder, so as to have its edge folded with the material thus forming a beaded effect in the extreme edge of the overseam. The other edge of the tape is so disposed preferably as to be engaged by the needle punctures, so that the needle stitches will pass through the tape close to its edge. The resulting article is shown in Fig. 9.

On the head of the machine is a second tape guide 22 which directs the tape to the tape guide 21.

While I have shown and described my invention as embodied in an organized overseaming machine, it is obvious that one of the essential features of the machine is the

throat plate on which is formed the upwardly projecting folder which not only serves the function of folding the edge of the material, but also as a stitch finger over which the stitches are laid. From certain aspects therefore, part of the present invention resides in the throat plate *per se*.
5

The trimmer is adjustable laterally in the manner shown and described in the patent 10 above referred to. By adjusting the trimming mechanism relative to the stitching mechanism and folder, I may vary the amount of material being folded.

It is obvious that minor changes in the 15 details of construction may be made without departing from the spirit of my invention.

Having thus particularly described my invention, what I claim as new and desire to 20 secure by Letters Patent, is:—

1. A sewing machine including in combination, feeding mechanism, overedge stitch forming mechanism for joining and covering the edges of fabric sections, a trimming 25 mechanism including trimming blades located in advance of the overedge stitch forming mechanism, a folder in rear of the trimming blades, said folder extending across the edges of the fabric sections and onto one 30 face of said sections, whereby the edges of said fabric sections are folded within the limits of the width of the overedge stitches, said folder being so positioned relative to the overedge stitch forming mechanism that 35 the stitches are laid over said folder and are fed off from the same onto the folded edges of the material.

2. A sewing machine including in combination, feeding mechanism, overedge stitch forming mechanism for joining and covering the edges of fabric sections, a trimming mechanism including trimming blades located in advance of the overedge stitch forming mechanism, a folder in rear of the trimming blade, said folder extending across the edges of the fabric sections and onto one 45 face of said sections, whereby the edges of said fabric sections are folded within the limits of the width of the overedge stitches, and a tape guide for guiding a tape to said folder, whereby said tape is partly inclosed by said folded edges of the fabric sections.

3. A sewing machine including in combination, feeding mechanism, overedge stitch forming mechanism for joining and covering the edges of fabric sections, a trimming mechanism including trimming blades located in advance of the overedge stitch forming mechanism, a folder in rear of the trimming blades, said folder extending across the edges of the fabric sections and onto one 55 face of said sections, whereby the edges of said fabric sections are folded substantially to and within the limits of the width of the overedge stitches, said folder being so posi-

tioned relative to the overedge stitch forming mechanism that the stitches are laid over said folder and are fed off from the same on to the folded edge of the material, and a stitch finger extending in rear of said 70 folder.

4. A sewing machine including in combination, a work support, feeding mechanism, overedge stitching mechanism, a folder for folding an edge of a material, and over which the stitches are laid, trimming mechanism in front of said folder for trimming the edge of the material before it is folded, said trimming mechanism including a lower trimmer blade having its cutting edge extending above the work support, said blade being tapered from its cutting point downwardly toward the work support, and also downwardly toward the front of the machine, whereby the edge of the material being trimmed is given a preliminary bend as it enters the folder.

5. A sewing machine including in combination, overedge stitch forming mechanism for joining and covering the edges of fabric 90 sections, a presser foot, a trimming mechanism including trimming blades located in advance of the overedge stitch forming mechanism, a throat plate, a folder mounted on said throat plate and located in rear of the trimming blades, said folder extending above and overlying the trimmed edges of the fabric sections for folding said edges substantially to and within the limits of the overedge stitches, said presser foot having 95 a cut out portion for said folder, a stitch finger carried by said folder and extending rearwardly therefrom, said folder being so disposed relative to said overedge stitch forming mechanism that the stitches are laid 100 over the folder and are fed off from said folder on to the stitch finger and the folded edges of the fabric sections.

6. A throat plate for sewing machines having a stitch finger and a folder formed integral therewith, said folder being disposed in advance of the stitch finger and projecting upwardly and over the throat plate, whereby an edge of fabric may be folded so as to be covered by overedge 110 stitches made around said stitch finger.

7. A sewing machine including in combination, feeding mechanism, overedge stitch-forming mechanism, a trimming mechanism including trimming blades located in advance of the stitching mechanism, a folder located in rear of the trimming mechanism and having a member extending above and over the edge of the material for folding the cut edge of the material to and within the limits of the overedge 120 stitches, said folder being disposed adjacent the stitch-forming mechanism, whereby the stitches are led over said folder and fed off from the folder on to the folded edge 125 130

4
of the material, and a presser foot having a fabric-engaging surface extending to a point in advance of the trimming mechanism and to a point in rear of the stitching mechanism, said presser foot being recessed 5 on one side to receive the trimmer and the folder.

8. A sewing machine including in combination, feeding mechanism, overedge 10 stitch-forming mechanism, a trimming mechanism including trimming blades located in advance of the stitching mechanism, a folder located in rear of the trimming mechanism for folding the cut edge 15 of the material, said folder being disposed adjacent the stitch-forming mechanism, whereby the stitches are led over said folder and fed off from the folder on to the folded edge of the material, a presser foot having 20 a fabric-engaging surface extending to a point in advance of the trimming mecha-

nism and to a point in rear of the stitching mechanism, said presser foot being recessed on one side to receive the trimmer and the folder, and a feed dog coöoperating with 25 said presser foot, said feed dog having a fabric engaging surface extending to a point in advance of the trimmer and to a point in rear of the folder.

9. The combination with a work support 30 including a stitch finger and a presser foot, of a concave-convex shaped member carried by one of said elements in advance of the stitch finger for receiving and turning the edge of a fabric section and for simultaneously supporting the overedge stitches. 35

In testimony whereof I affix my signature, in presence of two witnesses.
